Application December 5, 1951, Serial No. 17,618

Term of patent 14 years

(Cl. D33—7)

To all whom it may concern:

Be it known that I, William I. Lampel, a citizen of the United States, residing at 100 East 21st Street, Brooklyn, in the county of Kings and State of New York, have invented a new, original, and ornamental Design for a Combination File Cabinet and Desk or Similar Article, of which the following is a specification, reference being had to the accompanying drawing, forming part thereof.

In the drawing:

Fig. 1 is a front elevational view of a combination file cabinet and desk showing my new design; Fig. 2 is a top plan view thereof; Fig. 3 is a side elevational view thereof; and Fig. 4 is a fragmentary view taken in the plane of line 4—4 of Fig. 3 to show the outline of the part of the cabinet.

The side of the cabinet opposite the side shown in Fig. 3 is substantially like the side shown Fig. 3. The back of the cabinet is plain.

The dominant features of the design are shown in full lines.

I claim:

The ornamental design for a combination file cabinet and desk or similar article, as shown and described.

WILLIAM I. LAMPEL.
